UNITED STATES PATENT OFFICE.

CARMICHAEL IZETT, OF NEW YORK, N. Y.

LAUNDRY-BAG.

1,136,138.

Specification of Letters Patent. Patented Apr. 20, 1915.

Application filed January 8, 1914. Serial No. 810,962.

To all whom it may concern:

Be it known that I, CARMICHAEL IZETT, a citizen of the United States, and residing at New York, in the county of New York and State of New York, have invented certain new and useful Improvements in Laundry-Bags, of which the following is a specification, such as will enable those skilled in the art to which it appertains to make and use the same.

This invention relates to what are known as laundry bags, and the object thereof is to provide a bag of this class which is of novel construction and which may be suspended from a wall, the door of a wardrobe, or any other suitable support in an open condition so that articles to be washed may be easily thrown thereinto, or packed therein, from time to time; a further object being to provide a bag of the class specified which, when full, may be conveniently closed and sent to a laundry with the articles to be washed therein, and in which the washed or laundried articles may be returned to the owner of the bag by the laundry; and with these and other objects in view, the invention consists in a device of the class specified constructed as hereinafter described and claimed.

The invention is fully disclosed in the following specification of which the accompanying drawing forms a part, in which the separate parts of my improvement are designated by suitable reference characters in each of the views, and in which:

Figure 1 is a front view of my improved laundry bag and showing the method of suspending it in connection with a suitable support;—Fig. 2 a partial section on the line 2—2 of Fig. 1, and on an enlarged scale;—Fig. 3 a partial section on the line 3—3 of Fig. 1, and on an enlarged scale;—Fig. 4 a view on an enlarged scale of a detail of the construction shown in Fig. 1, and indicating the method of forming a name card pocket or holder which is also shown in Fig. 1;—Fig. 5 a partial section on the line 5—5 of Fig. 1, and on an enlarged scale;—Fig. 6 a section on the line 6—6 of Fig. 1, and on an enlarged scale, and Fig. 7 a diagrammatic view showing the method of forming the name card pocket or holder.

In the practice of my invention, I provide a bag *a* composed of canvas or any other suitable fibrous material and consisting of a back *b*, a front *c* connected with the back

b by folding sides *d* and between which and the back *b* is the main bag pocket *e*, and the front *c* is preferably provided with a supplemental pocket *f* consisting of a front member connected with the front *c* of the main pocket by folding the side members *g*.

The back of the bag is extended at the top thereof above the front *c* to form a flap *b*², and the top of the flap *b*² is folded inwardly to form three thicknesses, as shown at *b*³ in Fig. 6, and as indicated clearly in Fig. 4, the folding lines being shown at *b*⁴, *b*⁵ and *b*⁶, this folding producing the two main thicknesses of the fold, as indicated at *b*⁷ and *b*⁸ together with a narrow flange strip *b*⁹. The method of this fold and the parts produced are also indicated in Fig. 7, and the inner or front part *b*⁷ of said fold is provided with a name card holder centrally thereof, as shown at *b*¹⁰, and consisting of oppositely arranged pockets *b*¹¹, into which a name card may be inserted. In forming this name card holder, or the pockets *b*¹¹, the part *b*⁷ of the fold, which is the inner or face part, is cut to form triangular top and bottom flaps *b*¹², and triangular end flaps *b*¹³, and the end flaps *b*¹³ are folded inwardly or between the parts *b*⁷ and *b*⁸ of the fold, while the top flap is folded backwardly around the part *b*⁸ of the fold, and the bottom flap is folded inwardly or between the parts *b*² and *b*⁹, and the top and bottom edges of the open space between the pockets *b*¹¹ are stitched, as clearly shown in Fig. 1, the stitches extending entirely through the fold, and said fold is stitched transversely, as shown at *b*¹⁴ to hold the end flaps *b*¹³, and the fold is also stitched at the bottom thereof, as shown at *b*¹⁵, and the space *b*¹⁰ for a name card is thus formed without raw edges of any kind, as are also the pockets *b*¹¹ into which the ends of the name card are inserted.

The top portion of the front *c* of the bag is preferably a little wider than the top portion of the back, and at the opposite side edges thereof, the front portion is provided with pockets *h* to receive the ends of a detachable expansion bar *i* which is designed to hold the bag open at all times, and which may be easily inserted into position or removed by extending or stretching the front *c* slightly.

The sides *d* of the bag proper are made preferably of bellows form, as are also the sides *g* of the pocket *f*, and the width of the front *c* of the bag tapers downwardly

to the bottom, where it is practically of the same width as the back *b*. The sides *d* of the bag may also be of the same width from top to bottom, but are preferably tapered, as indicated in Fig. 1, and the top portions of said sides are inclined from the top of the back *b*, or the fold thereof, downwardly to the top of the front.

The top of the back, or the fold thereof, is provided with a row of eyelets *i*² which range transversely of the bag, and four of which are shown, and two hooks or similar devices may be connected with a support *j*, from which the bag may be suspended, and in which position the bag will be open at all times, and soiled clothes or other articles to be laundered may be thrown thereinto at any time until it is desired to send the bag, with its contents, to the laundry, when it may be detached from the support *j*.

The side edge corners of the front *c* are provided below the top thereof with eyelets *k*, and the opposite side edges of the back *b* are provided with corresponding eyelets *k*², and the top side corners of the supplemental pocket *f* are provided with similar eyelets *k*³, and a double draw cord *m* is passed through these eyelets, as clearly indicated in Fig. 1, and this cord incloses the sides *d*, and the back *b*, and in order to close the bag and secure it, all that is necessary is to detach the bar *i* and then draw the cord *m* tight and tie it in the usual manner, this operation will also, as will be understood, close the supplemental pocket *f*, and in this condition, the bag may be sent to the laundry, and when the contents have been laundered, the said laundered contents may be replaced in the bag, or in the pocket *f* and returned to the owner.

The supplemental front pocket *f* is not an absolutely essential feature of my improved laundry bag, but I prefer to employ it, in order that articles to be laundered may be separated when put in the bag, as, for instance, handkerchiefs, collars, cuffs and the like may be placed in the supplemental pocket *f*, and larger articles in the main bag or pocket *e*, and such articles may also be kept separate when returned by the laundry to the owner.

By extending the back *b* above the front *c*, the name plate *b*¹⁰ may be easily seen at all times, even when the bag is closed, and this construction also facilitates the hanging or suspending of the bag from a support, and facilitates the placing of articles to be laundered in the bag, and the support *j* may consist of the wall of a closet, or the door of a closet, or any other suitable surface on which the bag may be suspended, as shown and described.

Having fully described my invention, what I claim as new and desire to secure by Letters Patent is;—

1. A laundry bag composed entirely of flexible material and comprising a back, a front, and folding sides, the back being extended above the front and being provided at the top with a fold consisting of a plurality of thicknesses, and in the front thickness of which is a name card holder consisting of oppositely arranged pockets, said fold being also provided with a plurality of eyelets by which the bag may be suspended. 70

2. A laundry bag composed entirely of flexible material and comprising a back, a front and folding sides, the back being extended above the front and being provided at the top with a fold consisting of a plurality of thicknesses, and in the front thickness of which is a name card holder consisting of oppositely arranged pockets, said fold being also provided with a plurality of eyelets by which the bag may be suspended, 80 and said bag being also provided below the top of the front thereof and in the opposite side edge portions of the front and back and the folding sides, with eyelets through which is passed a draw cord by which the 90 bag may be closed.

3. A laundry bag composed entirely of flexible material and comprising a back, a front and folding sides, the back being higher than the front and being provided with a transverse row of eyelets, said bag being also provided below the top of the front and in the side edges of the front and back with eyelets through which is passed a draw cord, and the top of the bag 100 being provided at the front thereof with a transverse detachable expansion bar.

4. A laundry bag comprising a back, a front and folding sides, the back being raised above the front and being provided with transverse eyelets, the front portion of the bag being provided with a transverse detachable expansion bar, and the side edges of the front and side edges of the back being provided with eyelets below the top of 105 the front, and through which a draw cord is passed.

5. A laundry bag comprising a back, a front and folding sides, the back being raised above the front and being provided with transversely arranged eyelets, and a central name plate holder, the front portion of the bag being also provided at the top thereof with a detachable transverse expansion bar, and the front of the bag being also provided with a supplemental pocket, the side edges of the back and the side edges of the front being provided below the top of the front with eyelets, and the side edges of the supplemental pocket being also provided at the top thereof with eyelets and a draw cord passed through said eyelets. 120

6. A laundry bag formed entirely of flexible material and comprising a back, a front and folding sides, forming a pocket, the 130

- back extending above the pocket and being provided at its upper edge with a transverse row of eyelets, the outermost eyelets of said row being in close proximity to the lateral edges of the back, by means of which the bag may be suspended in an open position, the back lateral edges and the front lateral edges of the bag being provided below the top of the pocket with eyelets adapted to receive a draw cord, whereby the bag after being removed from its supports, may be closed.
7. A laundry bag composed entirely of flexible material and comprising a back, a front and folding sides forming a pocket; the back being extended above the pocket and being provided at the top thereof with a transverse row of eyelets by means of which it may be suspended in an open position, the back side edges of the bag and the front side edges thereof being provided below the top of the pocket with eyelets through which is passed a draw cord, and means for expanding the pocket when the bag is suspended.
8. A laundry bag composed entirely of flexible material and comprising a back, a front and folding sides, the back being extended above the front and provided with a transverse row of eyelets, and the front being provided with a supplemental pocket, the back side edges of the bag, the front side edges thereof and the top front side edges of the supplemental pocket being also provided with eyelets through which is passed a draw cord.
9. A laundry bag composed entirely of flexible material and comprising a back, a front and folding sides, the back being extended above the front and being provided at the top with a fold consisting of a plurality of thicknesses, and the front thickness being provided with a name card holder, said fold being also provided with a plurality of eyelets by which the bag may be suspended in an extended position.
10. A laundry bag composed entirely of flexible material and comprising a back, a front and folding sides, the back being extended above the front and being provided at the top with a fold consisting of a plurality of thicknesses, and the front thickness being provided with a name card holder, said fold being also provided with a plurality of eyelets by which the bag may be suspended in an extended position, and said bag being also provided at the top thereof and in the front and back edges thereof with eyelets through which is passed a draw cord.

In testimony that I claim the foregoing as my invention I have signed my name in presence of the subscribing witnesses this 6th day of January 1914.

CARMICHAEL IZETT.
